AUTOMATIC REPLENISHING-LOOM.

1,123,141.

Specification of Letters Patent. Patented Dec. 29, 1914.

Application filed February 27, 1914. Serial No. 821,540.

To all whom it may concern:

Be it known that I, ALONZO E. RHOADES, a citizen of the United States, residing at Hopedale, county of Worcester, State of Massachusetts, have invented an Improvement in Automatic Replenishing-Looms, of which the following description, in connection with the accompanying drawing, is a specification, like characters on the drawing representing like parts.

This invention relates to improvements in looms provided with mechanism to effect automatically a change in the operation of the loom when the filling on the active shuttle is substantially exhausted. This change in the operation of the loom may be in the stoppage thereof or it may be, and more frequently is, the replenishment of the filling in the working shuttle. In looms of this character the controlling mechanism is arranged to coöperate with a feeler which is adapted to automatically enter the working shuttle and "feel" upon the filling upon the filling carrier as the lay comes forward to beat up the filling. Upon substantial exhaustion of the filling upon the filling carrier a bunter carried by the feeler contacts with the side of the shuttle or of the shuttle box and thereupon actuates a controller either directly or indirectly to initiate the operation of the mechanism, which effects the change in the operation of the loom. It is found that the change in operation of the loom is occasionally falsely called for by the feeler and the loom stopped or transfer effected while a considerable amount of filling remains upon the filling carrier. This causes a loss of the time required to attend and restart the loom, or a waste of filling by the premature discharge of the filling carrier from the shuttle.

One of the objects of this invention is to provide means which are adapted to effect the proper change in the operation of the loom upon actual substantial exhaustion of the filling upon the filling carrier but which will not be operated by a false detection of absence of filling by the feeler. In the preferred embodiment of my invention disclosed herein this is accomplished by providing means whereby the change in the operation of the loom will be initiated only after a plurality of successive detections by

the feeler of substantial exhaustion of filling upon the filling carrier. 55

Another object of the invention is to provide means for restoring the feeling mechanism to normal position if the feeler fails to detect substantial exhaustion of filling upon each of a plurality of successive 60 "feels."

Another object of the invention is to provide means for controlling the movable member which is actuated by the feeler to initiate a change in the operation of the 65 loom in such a manner that a greater amount of resistance will be interposed against the first movement of said member than against a subsequent movement thereof, whereby 70 overthrow upon the first movement which might initiate transfer will be avoided, and the full throw to effect transfer upon a subsequent movement made with relatively little resistance in order that the change in 75 the operation of the loom may be initiated with certainty.

Other objects of the invention will more fully appear from the following descriptions and accompanying drawings and will be pointed out in the claims. 80

In the drawings, Figure 1 is a general plan view, partly broken away of a loom embodying my invention, Fig. 2 is a plan view of the feeler mechanism, Fig. 3 is a vertical longitudinal sectional view of the 85 same, Fig. 4 is a side elevation thereof.

The invention is illustrated herein in connection with the usual type of Northrop loom such as that shown in U. S. Patent No. 789,471 granted May 9, 1903 to Wood and Northrop and comprises the usual frame and breast beam 1, a lay 2, provided with a shuttle box and shuttle 3 inclosing the usual filling carrier 4 which is illustrated in the drawing as a bobbin. The 90 shuttle box and the shuttle are apertured to permit the entrance of the feeler in the usual manner. 95

The battery end of the loom as illustrated in Fig. 1 comprises a carrier 5 having a plurality of bobbin supports and a transfer arm 6 which is adapted to be actuated through a controller shaft 7 having a vertically extending arm 8 to which is pivoted a latch 9 adapted to be positioned in the 100 path of the weft hammer 15 by a transmit- 105

ter 10 having a lateral projection 11 forming a cam slot inclosing a pivoted controller 12 adapted to be operated by the feeler 14 through a movable member 13 upon detection by the feeler of substantial exhaustion of filling upon the filling carrier.

The loom may be provided with the usual feeling fork 16 carried by a slide 17 and adapted upon detection of absence of filling 10 to actuate the transfer arm through the member or "grasshopper" 18 in the manner usual in the Northrop type of looms.

A shuttle feeler and thread cutter is also illustrated in Fig. 1 in its position at the 15 battery end of the loom while the opposite end is provided with the usual shipper plate extension 21 above which is mounted a lever 20 which is adapted to engage a shipper 22 slidably mounted in a slot 23 in 20 said plate. The feeler mechanism is preferably mounted upon a stand at the end of the shipper plate.

The construction thus described may be 25 of the usual character and forms no part of the present invention.

In the feeling mechanism of the character heretofore used an actuator carried by the feeler has been provided to engage the controller either directly or indirectly and 30 cause the latter to initiate the change in the operation of the loom upon detection of substantial exhaustion of filling upon the filling carrier, but it has been found that in many instances the feeler will falsely indicate 35 an exhaustion of filling and call for a change in the operation of the loom such as a transfer of the filling carrier in the shuttle or the stoppage of the loom, thus causing in the first instance a waste of filling and in the 40 second a loss of the time required for the attendance and restarting of the loom. By the present invention means are provided whereby the likelihood of causing such a premature change in the operation of the 45 loom is avoided, by interposing between the controller and the feeler certain mechanism which will require a plurality of successive detections by the feeler of substantial exhaustion of filling, before the mechanism 50 which causes the change in the operation of the loom will be called upon to perform its function.

In the preferred form of invention illustrated herein a slide is interposed between 55 the actuator carried by the feeler and the controller and means are provided whereby the actuator will be given only a preliminary movement upon detection of absence of filling, and will require a series of successive 60 engagements by said actuator to move it sufficiently far to cause the controller, operating through the transmitter, to position the latch in the path of the weft hammer, means are also provided to restore the 65 slide to normal position if the actuator fails

to advance said slide upon successive movements of the feeler.

The preferred form of feeler mechanism embodying my invention as illustrated herein comprises a stand having a base portion 70 25 and a top portion 26 secured together in a suitable manner, and chambered out to form a slideway for the feeler 27 which is held in extended or feeling position by a spring 28. The forward end of the feeler 75 25 is provided with a feeling head 29 and is slotted intermediate of the head portion and the stand to receive an actuator 30 which is mounted upon a pin or bolt 31 extending across said slot. The actuator 30 comprises 80 an arm offset from, but extending in a plane parallel to the plane of the feeler and is provided with an upward projection or lug 32 parallel to the offset. A bolt 33, the head of which is adapted to form a bunter, is 85 suitably secured in said lug and the offset portion of the actuator by means of screw threaded connections, and may be clamped in position by a nut 34. The end portion of the actuator preferably extends parallel to 90 the feeler 27 and is provided at its tip with a notch 36 which is adapted to engage a suitable slide to actuate the controller in a manner hereinafter to be described. The upper portion of the stand is preferably 95 provided with a loop against which the arm of the actuator is pressed by a spring 35 secured to the underside of the feeler.

The feeler is provided with an extension 37 preferably cylindrical in form inclosed 100 by the spring 28 which maintains the feeler normally in feeling position. This extension projects slightly beyond the end of the stand 26, and the end thereof is notched to form a shoulder or catch 38 adapted to co-operate with a latch carried by the sliding member 13 in a manner which will herein-after be described.

At the junction of the feeler 27 with its cylindrical extension 37 a laterally extending plate 40 is preferably provided having an upstanding lug 41 adapted to be engaged by the end of the controller 12 and which will normally hold said controller in inoperative position.

The top of the upper portion 26 of the stand is provided with a slideway in which is mounted a slide 13, this slide being preferably composed of a member 50 fitting in said slideway and provided with a superposed plate 51 rigidly secured thereto and having a beveled end portion 53 at the forward end and a recess or notch 54 at the rear end, said notch providing a shoulder 55 adapted to be engaged by the actuator upon 120 detection of absence of filling in the filling carrier. The extreme forward end of the sliding member 51 forms a like shoulder 56 adapted to be engaged by the actuator. The 125 rear end of the member 51 is preferably 130

provided with a downward projection 57 which is adapted to engage the end of the controller 12 and force the same forward after the slide 13 has been sufficiently advanced to permit the projection 57 to engage said controller.

In the embodiment of the invention illustrated herein but two shoulders upon the sliding member adapted to be engaged by the actuator are shown but it will be obvious that any desirable number of shoulders may be provided or that other means may be provided whereby the movable members may be engaged by the said actuator. In order that the controller shown herein may be moved to sufficiently initiate a change in the operation of the loom it is necessary that the feeler shall detect substantial absence of filling upon the filling carrier and cause the engagement of the actuator with the shoulders 55 and 56 in succession.

It is of course necessary that sufficient resistance be provided to prevent the slide from overthrowing and thereby causing premature transfer and also to prevent the rebounding of the slide when advanced to the limit of its movement. To effect this result, the slide is preferably provided with differential frictional members adapted to interpose resistance of different degrees against the movement of the slide so that the preliminary movement of the slide will be caused to cease immediately upon the disengagement of the actuator, but the final movement of the slide to actuate the controller will meet with little resistance. As illustrated herein the sliding member 13 is secured in the slideway by a stud or bolt 60 which extends from the upper portion of the stand 26 upwardly through a slot in the sliding member 51, the upper end of the bolt or stud 60 being provided with a washer 61 and nut 62. The friction member preferably consists of a stud 65 likewise projecting upwardly from the upper portion of the stand 26 and provided with a washer 66 resting upon the upper surface of the member 51, said washer 66 being forced down upon said surface by a spring 67 which may be adjusted to greater or less tension by suitable set nuts 68.

It will be observed by reference to Fig. 3 that when the slide 13 is in normal position the washer 66 will rest against the inclined surface 53 of the sliding member 51 and it will be obvious that when the slide is first advanced by the engagement of the actuator 30 with the shoulder 55 on the sliding member a considerable amount of resistance will be presented to such movement, but upon the second engagement of the actuator with the shoulder 56 of the sliding member the washer will have reached the horizontal portion of the upper surface of the slide member and a less degree of resistance

will be presented to the movement of the sliding member. By this arrangement sufficient force is always exerted upon the feeler to prevent overthrow upon the first detection by the feeler of substantial exhaustion of filling upon the filling carrier, but the slide is permitted to work more freely upon the subsequent engagement of the feeler to move the controller.

Inasmuch as it is desirable that a change in the operation of the loom shall be effected only upon a plurality of successive engagements by the actuator with the sliding member it is necessary to provide means for returning the sliding member to normal position if the actuator fails to engage the sliding member upon successive reciprocations of the feeler. In the preferred form of invention illustrated herein the slide 13 is provided with an upwardly extending lug 70 in which is journaled a shaft 71 provided at its end with a latch 72 having a downwardly projecting end 73 normally supported by an inclined surface 74 in the member 26 directly over the rearwardly extended end 37 of the feeler. The shaft 71 is preferably provided with a spring 75 attached to the lug 70 and to a collar 76 which is suitably supported upon the end of the shaft 71, said spring having the function of maintaining the latch 72 in a depressed position so that when the slide is moved forwardly by the action of the feeler the downwardly projecting end 74 of the latch 72 will extend into the path of the catch 38 carried by the rearward extension of the feeler. So long as the bunter 35 contacts with the side of the shuttle or shuttle box to force the actuator into engagement with the sliding member the latter will be forced forward in unison with the feeler and the catch 38 will not extend beyond the latch 73, but if after the first engagement of said actuator with the shoulder 55 of the sliding member, the bunter fails to throw the actuator into engagement with the shoulder 56 of said sliding member, the catch 38 will be forced beyond the end 73 of the latch and upon the feeler being returned to "feeling" position by the spring 28 said catch will engage the end 73 of the latch and return the sliding member with it to normal position. When the latch substantially reaches normal position the under face of the latch 73 rides upon the inclined surface 74 out of engagement with the notch 38 and permits the feeler to return to normal position.

It is to be understood that the particular embodiment of the invention disclosed herein is illustrative merely and not restrictive and that my invention comprehends any mechanism in which a feeler is required to detect absence of filling successively during a plurality of reciprocations of the feeler before the feeling mechanism will be suffi-

ciently operated to initiate a change in the operation of the loom.

Having thus described my invention what I claim as new and desire to secure by Letters Patent is:

1. Feeling mechanism for looms comprising a stand, a feeler mounted thereon, an actuator carried by said feeler, a relatively movable member adapted to be engaged by said actuator upon each detection by the feeler of substantial exhaustion of filling upon the filling carrier, and means whereby said member will be actuated only by a plurality of successive engagements of said actuator upon detection of absence of filling to initiate a change in the operation of the loom.

2. A feeling mechanism for looms comprising a stand, a feeler mounted thereon, an actuator carried by said feeler, a relatively movable member adapted to be engaged by said actuator upon detection by the feeler of substantial exhaustion of filling upon the filling carrier, means whereby said member will be actuated only after a plurality of successive engagements of said actuator to initiate a change in the operation of the loom, and means for restoring said member to normal position unless the same is engaged by said actuator upon each of said plurality of successive movements of said feeler.

3. An automatic filling replenishing loom having a transferring mechanism, means for operating the same to effect the introduction of a fresh filling carrier comprising a feeler, and means adapted to be operated thereby to initiate the action of the transfer mechanism only after a plurality of successive detections by said feeler of substantial exhaustion of filling upon the filling carrier.

4. In an automatic filling replenishing loom having a transferring mechanism, means for operating the same to effect the introduction of a fresh filling carrier comprising a feeler, an actuator carried thereby, a movable member adapted to be engaged by said actuator upon detection by said feeler of substantial exhaustion of filling upon the filling carrier of the active shuttle, and means whereby said member will be sufficiently actuated only after a plurality of engagements by said actuator to initiate the action of the transfer mechanism.

5. Feeling mechanism for automatic filling replenishing looms comprising a stand, a feeler slidably mounted thereon, a relatively movable member mounted upon said stand independently of said feeler, an actuator carried by said feeler, adapted to engage and move said movable member upon detection by the feeler of substantial exhaustion of filling upon the filling carrier,

means for arresting the movement of said member and means whereby said actuator will reengage and move said member upon a second successive detection by said feeler of absence of filling sufficiently to actuate said transfer mechanism.

6. Feeling mechanism for automatic filling replenishing looms comprising a stand, a feeler slidably mounted upon said stand, a sliding member mounted upon said stand independently of said feeler, an actuator carried by said feeler adapted to engage said sliding member upon detection by the feeler of substantial exhaustion of filling upon the filling carrier, means for arresting the movement of said slide, means whereby said actuator will reengage and move said sliding member upon a second successive detection by said feeler of absence of filling to actuate said transfer mechanism, and means for restoring said slide to normal position unless the same is engaged by said actuator upon each of a plurality of successive movements of said feeler.

7. Feeling mechanism for looms comprising a stand, a feeler slidably mounted thereon, having a rearwardly extending catch, a sliding member having a plurality of engaging elements mounted on said stand independently of said feeler, an actuator carried by said feeler adapted to engage an element of said sliding member to move the latter upon detection by said feeler of substantial absence of filling on the filling carrier, a brake adapted to arrest said sliding member upon the disengagement of said actuator and means adapted to be actuated by said sliding member only after a plurality of successive engagements of said actuator therewith to effect a change in the operation of the loom.

8. Feeling mechanism for looms comprising a stand, a feeler slidably mounted thereon, having a rearwardly extending catch, a sliding member having a plurality of engaging elements mounted on said stand independently of said feeler, an actuator carried by said feeler adapted to engage an element of said sliding member to move the latter upon detection by said feeler of substantial absence of filling on the filling carrier, a brake adapted to arrest said sliding member upon the disengagement of said actuator and means adapted to be actuated by said sliding member only after a plurality of successive engagements of said actuator therewith to effect a change in the operation of the loom, and means carried by said sliding member adapted to be engaged by the catch on said feeler to restore the sliding member to original position unless moved by said actuator upon each successive reciprocation of said feeler.

9. Feeling mechanism for looms comprising a feeler, a movable member adapted to

be advanced thereby upon detection of absence of filling and upon a plurality of advances to initiate a change in the operation of the loom and of coöperating means carried by said feeler and said movable member adapted to restore said movable member to normal position unless advanced by successive movements of said feeler.

10. Feeling mechanism for looms comprising a feeler and a movable member adapted to be advanced thereby and upon a plurality of successive detections of substantial exhaustion of the filling upon the filling carrier to effect a change in the operation of the loom, a brake for said movable member adapted to present different degrees of resistance to the movement of said movable member whereby initiation of the change in the operation of the loom is prevented

15 upon the first detection by said feeler of absence of filling and is permitted upon a subsequent successive detection thereof.

11. Feeling mechanism for looms comprising a feeler and a movable member adapted to be advanced thereby and upon a plurality of successive detections of substantial exhaustion of the filling upon the filling carrier to effect a change in the operation of the loom, a brake for said movable member adapted to present different degrees of resistance to the movement of said movable member whereby initiation of

the change in the operation of the loom is prevented upon the first detection by said feeler of absence of filling and is permitted 35 upon a subsequent successive detection thereof comprising relatively inclined surfaces upon the sliding member and a spring actuated braking member and means permitting a relatively sliding movement between said 40 members.

12. Feeling mechanism for looms comprising a stand, a spring actuated feeler mounted thereon having a rearward extension, a sliding member mounted on said stand independently of said feeler and having a plurality of shoulders, an actuator carried by said feeler adapted upon detection of absence of filling in the filling carrier to engage a shoulder on said sliding member to 50 advance the same, a brake for said sliding member, and a latch pivoted upon said sliding member adapted to engage said feeler extension and restore said sliding member to normal position when the same is not 55 engaged by said actuator.

In testimony whereof I have signed my name to this specification, in the presence of two subscribing witnesses.
